RECOVERABLE TAMPING PLUG

Benjamin F. Sanders, Rte. 1, Branchland, W. Va.
Filed Mar. 27, 1959, Ser. No. 802,351
3 Claims. (Cl. 102—30)

This invention comprises a novel and useful recoverable tamping plug and more particularly relates to an improved tamping plug adapted to tamp and retain blasting charges in a shot hole in an improved manner, and which may be recovered for re-use.

The primary purpose of this invention is to provide a tamping plug which shall have an improved tamping action in a shot hole for retaining a blasting charge therein during the blasting operation; and which shall be capable of repeated re-use.

A further object of the invention is to provide a tamping plug which shall include thereon means whereby the plug may be readily separated from the material shot down by the blast and recovered for subsequent re-use.

A further and more specific object of the invention is to provide a tamping plug in accordance with the foregoing objects which shall be entirely constructed of a resiliently yieldable and deformable material such as rubber or the like and which shall obtain an improved and more effective sealing engagement with the wall of the shot hole during the blasting operation.

Another specific object of the invention is to provide a tamping plug in accordance with the foregoing objects which shall have mounted thereon one or more elements of a magnetic material whereby the tamping plug may be recovered by electromagnetic means as the material shot down by the blast with the plugs therein are passed in close proximity to an electro-magnet.

Still another and more specific object of the invention is to provide an improved tamping plug consisting of an elongated rod-like body of rubber or other resiliently yieldable and deformable material having integral annular sealing rings along the length thereof together with a plurality of bands or rings of a magnetic material loosely encircling the body whereby the plug may be readily recovered from the material shot down by the blast when the material and the plug are passed in close proximity to an electro-magnet.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a view showing in vertical section a portion of a blast hole in a formation together with a tamping plug in accordance with this invention applied in the blast hole for retaining a blasting charge therein;

FIGURE 2 is a perspective view of the improved tamping plug in accordance with the invention and as shown in FIGURE 1.

FIGURE 3 is a view in vertical central longitudinal section taken upon an enlarged scale substantially upon the plane indicated by the section line 3—3 of FIGURE 2 and with a portion thereof being broken away;

FIGURE 4 is a vertical transverse sectional view taken upon an enlarged scale substantially upon the plane indicated by the section line 4—4 of FIGURE 2.

FIGURE 5 is an elevational view illustrating the manner in which a modified construction of tamping plug in accordance with this invention is removed from the material shot down by the blast when the material and plug are passed in proximity to an electro-magnet;

FIGURE 6 is an elevational view of the modified tamping plug employed in accordance with the method indicated in FIGURE 5;

2

FIGURE 7 is a detail view in vertical central section taken substantially upon the plane indicated by the section line 7—7 of FIGURE 6; and

FIGURE 8 is a vertical transverse sectional view taken substantially upon the plane indicated by the section line 8—8 of FIGURE 6.

Referring now to FIGURE 1 it will be observed that the numeral 10 indicates a portion of a vein or other deposit of material which it is desired to break up and recover as by blasting, while the numeral 12 indicates a blast or shot hole therein. A blasting charge shown at 12 is shown tamped in this hole by the improved tamping plug of the present invention indicated generally by the numeral 14.

Referring now to FIGURES 2 and 3 in particular it will be observed that the tamping plug consists of a rod-like element 20 which is preferably of uniform diameter throughout its end except for the provision of a plurality of longitudinally spaced annularly enlarged sealing rings as at 22. In addition, at its outer end the body 20 is provided with a diametrically enlarged flange or head portion as at 24 while the inner end of the body is diametrically enlarged as at 26 but of a diameter still less than that of the rings 22 or the head 24, and this diametrically enlarged end portion is provided with a reversely tapered conical surface as at 28 and 29. Upon its inner end, the enlargement 26 is provided with a recess or cavity 30 which is adapted to abut against and tightly engage the charge 14 in the position shown in FIGURE 1. In some instances, the tamping of the plug against the charge will result in causing the deformable yieldable material of the enlargement 26 to act as a suction cup and retain the plug against the charge.

The annular enlarged ribs or rings 22 of the plug are provided with dished surfaces as at 32 upon their sides 35 which are adjacent to the head 24 while the opposite sides of the plug are provided with doubled edges as at 34. This construction causes the ribs to yield as the plug is tamped or driven into the shot hole 12 and thus insuring the establishing of a tight sealed engagement of the tamping plug with the wall of the hole. In a similar manner, the inward surface of the head 24 is likewise beveled as at 36 for the same purpose. The tapered end 28 assists in guiding the tamping plug into the shot hole as previously mentioned.

In this form of the invention the rubber plug when driven tightly against the blasting charge 14 will by virtue of the flexing of its fins, ribs or enlargements 22 against the wall of the shot hole effect a tight seal engagement therewith. In addition, the suction cup effect of the cavity 30 will assist in retaining the tamping plug tightly against the charge once the same is tamped into place.

After the blasting charge 14 is set off in the usual manner, the force of the expanding gases being retained 55 by the tamping plug will disrupt or shoot down the formation 10 and thus break up the material of the same. Thereafter, when this material is removed from the sight of the blasting operation, the rubber tamping plugs can be recovered therefrom in any suitable manner and owing to their resilient nature will be suitable for re-use again and again.

However, shown in FIGURES 5—8 is a preferred embodiment of tamping plug in accordance with this invention which will facilitate the recovery of the plug by 65 mechanical means. In this embodiment, it will be understood that the plug indicated generally by the numeral 50 likewise is an elongated rod-like body preferably of a resiliently yieldable deformable material such as rubber or the like. Intermediate its ends and in longitudinally spaced relation therealong the body is provided with a plurality of annular laterally projecting ribs, fins or flanges

as at 52 which establish a resilient seal with the wall of the shot hole in which the plug is inserted. At its opposite ends the plug is provided with diametrically enlarged end portions as at 54, one of which is adapted to be positioned closely adjacent to or abutting against the blasting charge while the other end comprising the outer end of the tamping plug is employed to tightly drive the plug into engagement with the charge. The body portion 56 of the plug has been illustrated as being of uniform diameter. It will be understood, however, that this body may be of any desired cross sectional shape or area and may be of a variable thickness or diameter depending upon the circumstances in which the plug is to be employed.

Although the annular sealing flanges or ribs 52 and the ends 54 are shown as being rectangular in cross-section as seen in FIGURE 7 and it will be understood that they may be of the same construction shown in FIGURE 3, so that the dished surfaces 32, the bevel surfaces 34, 36, the tapered surfaces 28 and 29 and the recess 30 may all likewise be employed.

At longitudinally spaced positions along a rod-like body 56 there are secured magnetic elements 60. Preferably these elements 60 are in the form of loosely encircling bands or rings which are received upon the body between adjacent rings of flanges 52 or between the latter and one of the ends 54. In some instances, however, the rings 60 may be tightly secured to the rod-like member as by being embedded in annular grooves therein or the like. In other instances, the magnetic elements may be in the form of separate bodies of magnetic material embedded in or secured in any desired manner to the body portion of the tamping plug.

The purpose of the application of the magnetic elements to the body will be readily apparent from FIGURE 5. After the blasting charge has been set off and the material 10 has been shot down from the face of the blasting operation, the thus broken up material as at 70 in FIGURE 5, with one or more of the plugs 50 disposed therein is caused to pass with the material into close proximity to an electro-magnet as at 72. This magnet will attract the magnetic material of the plugs passing in close proximity thereto and thus draw or remove the plug from the material whereby the plugs may be reclaimed for further use. It will be understood that the electro-magnetic recovery device may be disposed in any suitable position as in a colliery if the plugs are employed in the blasting of coal, or anywhere along the passage of the shot material.

The foregoing is considered as illustrative only of the

principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A recoverable and reusable tamping plug for blasting comprising a unitary elongated rod-like and solid body of a non-magnetic resiliently yieldable and deformable material for insertion in shot holes, integral annularly enlarged sealing rings on said body in longitudinally spaced relation thereon and of a diameter and resiliency sufficient to enter a shot hole and thereafter establish a sealing engagement with a shot hole wall in which the tamping plug is inserted, a magnetic element surrounding said body between a pair of adjacent rings whereby to facilitate recovery of the plug from the material shot down by the blast with a magnetic plug recovery device, a tapered inwardly recessed inner end on said plug to facilitate its insertion into a shot hole and its position against a blasting charge therein.
2. The combination of claim 1 including a pair of longitudinally spaced magnetic elements mounted upon said plug each at one end thereof whereby to effect recovery of said plug from the material shot down by the blast with a magnetic plug recovery device.
3. The combination of claim 1 including a plurality of longitudinally spaced magnetic elements mounted upon said plug whereby to effect recovery of said plug from the material shot down by the blast with a magnetic plug recovery device, said elements comprising bands disposed each between a pair of adjacent rings and of less diameter than that of said rings and loosely encircling said plug.
